UNITED STATES PATENT OFFICE.

MARIETTA REECE AND FRANCIS A. SHEA, OF BROOKLINE, MASSACHUSETTS,
ADMINISTRATORS OF JOHN REECE, DECEASED.

BUTTONHOLE SEWING AND CUTTING MACHINE.

SPECIFICATION forming part of Letters Patent No. 655,637, dated August 7, 1900.

Application filed July 8, 1898. Serial No. 685,403. (No model.)

To all whom it may concern:

Be it known that JOHN REECE, deceased, late of Brookline, Massachusetts, did invent an Improvement in Buttonhole-Sewing Machines, of which the following description, in connection with the accompanying drawings, is a specification, like letters on the drawings representing like parts.

This invention is intended as an improvement upon United States Patent No. 494,280, dated March 28, 1893, and United States Patent No. 498,216, dated May 23, 1893. Patent No. 494,280 describes a buttonhole-stitching mechanism wherein the buttonhole made has an enlarged eye, the stitching being commenced at the small end of the slit and being carried along the side of the slit, thence about the eye, the stitching mechanism at such time having given to it a semirotation, and then 15 the stitching is resumed along the opposite side of the slit, the stitching being terminated at the small end of the slit, the barring being thereafter done on a separate machine. In the Patent No. 498,216 the stitch-forming 20 mechanism is described as having imparted to it for the production of each buttonhole two semirotations, the first semirotation finishing the enlarged or eye end of the buttonhole, the second semirotation barring and 25 finishing the small end of the buttonhole, the operation of the stitch-forming mechanism being stopped after stitching about the small end of the hole, such stitching barring that 30 end of the hole, the barring-stitches being the same as those made along the side of the slit, but the barring-stitches cross the line of 35 the buttonhole-slit.

To use the machine described in the latter patent, work was put into the open clamp, 40 the clamp was closed, the shaft having the worm for moving the stitch-frame was started at its highest speed, and said shaft turned a cam which actuated the cutting mechanism to cut the material held in the clamp, and, 45 that done, the cam in its further rotation, the high speed of its shaft being continued, moves the stitch-frame quickly into proper position with relation to the cut buttonhole held in said clamp and the stitch-forming mechanism is started into operation, the shaft referred to at such time being put under the

control of other driving mechanism which imparts to said shaft and the cam actuated by it a slower step-by-step movement, this slower movement being continued while 55 stitching the buttonhole. The stitching of the buttonhole was started close to one end of the slit and was continued along the edge of the buttonhole to the point of starting, said stitching crossing both ends of the buttonhole and crossing the point of starting. During the overstitching of the slit the stitch-forming mechanism had given to it a more or less straight movement, according to the particular shape desired for the eye of the buttonhole, and the stitching mechanism had imparted to it two semirotations, said stitching 60 completing and barring the buttonhole.

In the patent referred to, owing to the fact that the buttonhole-stitching mechanism was 70 rotated always in the same direction rotation after rotation, it became necessary to add to the machine peculiar thread-controlling means for the under thread, which complicated the machine and made it difficult to 75 maintain the thread in its proper twisted condition, and, further, to impart to the stitch-forming mechanism a continued rotation in one direction only necessitated the employment of gears which were moved step by step 80 by a ratchet mechanism, such mechanism and gears resulting in lost motion, so that the accurate commencement and stopping of the buttonhole could not always be insured.

This present invention is designed to obviate the difficulties experienced in the operation of the machine referred to in said patent. Herein the stitch-forming mechanism instead of being rotated continuously in one direction rotation after rotation has imparted to it two semirotative movements and two more or less straight movements alternately with said semirotations in the production of each buttonhole, and the stitch-forming mechanism is stopped after the completion of its 95 second semirotation, and thereafter, preparatory to stitching another buttonhole, the stitch-forming mechanism, having been rotated for a distance usually in excess of one complete rotation, is reversed in the direction of its movement and is brought again to its normal starting-point, the return move-

ment of the stitch-forming mechanism being herein represented as accomplished automatically, to thereby provide for operating the machine always at a high speed. To reverse the movement of the stitch-forming devices, mechanism is employed somewhat resembling that shown in United States Patent No. 494,280; but to enable the mechanism to operate as herein provided for the mechanism shown in said patent for imparting the semicircular movement to the stitch-forming mechanism had to be materially altered and modified, so that said mechanism might be moved for more than one full rotation and then be reversed into its normal starting position, and said altered mechanism operated in the manner herein to be described results in producing a machine having a new mode of operation.

By the means employed in Patent No. 494,280 the stitch-forming mechanism in following the line of the buttonhole would have imparted to it only one semirotation; but herein by modifying the construction of the mechanism employed for imparting semirotative movement to the stitch-forming mechanism it has become possible to impart to said stitch-forming mechanism two semirotations progressively at the proper time and to thereafter reverse the motion of said mechanism, returning it to its starting position. This operation has been rendered possible by making the bar, rod, or device used to connect the two sector-levers employed for imparting semirotative movement to both the needle-bar and the under-thread-carrying mechanism the fulcrum for said two levers, said alteration of the fulcrum of these two sector-levers, together with the change of the shape of the path-cam for operating one of them, enabling the stitch-forming mechanism to have a full or a little more than a full rotation imparted to it in the operation of forming each buttonhole. The lower sector-lever connected with this common fulcrum and employed to impart semirotative movements to the under-thread-carrying mechanism has an arm to which in the case of this invention is attached a link actuated by a lever moved by the usual cam contained in the casing, whereas in the Patent No. 494,280 the said sector-lever had a cam-roll which entered a groove in the said cam. In this invention means have been provided to not only adjust the connection of this link with the arm of the sector-lever, but also to adjust the roller-stud on the lever used to actuate said link, whereby the sectors may be started sooner or later, and thereby insure the starting of the stitching at exactly the proper point. Patent No. 494,280 contains a shaft which is rotated intermittently during the stitch-forming operation; but said shaft after the buttonhole has been stitched is rotated continuously to effect rapidly the proper relative change of the stitch-forming mechanism with relation to the work-clamp, holding the work-clamp

so that the stitch-forming mechanism is put into position to enable the buttonhole to be cut and to again enable the stitching mechanism to be brought into position to again start the stitching for the next buttonhole. In Patent No. 494,280 the shaft referred to has a continuously-rotating clutch-pulley, which is automatically put out of clutch to let the shaft be moved intermittently for stitching by means of a lever pivoted at the under side of the clamp-frame, said lever deriving its movement from suitable levers of a rock-shaft under the control of an actuating device or a starting or stopping clutch carried by the main shaft, which imparts motion to the stitch-forming mechanism, and said pulley was put into clutch to rotate said shaft by or through the movement of a lever located at or near the cloth-clamp, said lever being moved by the insertion of the work in the clamp, and in its movements a bar was released controlled by a spring, said bar when released moving the lever in a direction to put the clutch-pulley in engagement. Herein the lever referred to as pivoted to the underside of the clamp-frame has been materially modified in its construction, shape, and method of operation.

During the operation of stitching a buttonhole the usual rock-shaft which controls the time of starting and stopping the stitch-forming mechanism acts by one of its arms against the portion of a lever having an incline, said lever being connected at or near its incline with one part of the clutch for imparting at desired times more rapid speed to the shaft for moving the stitch-frame; but when the stitch-forming mechanism is to be thrown out of operation, as it is when the last stitch of the buttonhole is made and at which time the clamp is opened, the arm referred to of said rock-shaft retires from contact with the lever having the incline, letting a spring move said lever in a direction to effect the clutching together of the clutch for imparting the rapid movement to said shaft and stitch-frame. As the clamp is open a projection controlled by it comes opposite the inner end of a lever which has been added to the present machine, it being pivoted upon the under side of the clamp-frame and holding said lever provided with the incline in a fixed position, so that a stud at the opposite end thereof is put in position to constitute a rigid abutment. As soon as the clutch is engaged the stitch-frame is started up at its most rapid speed and the lever having the incline moves with it and said incline acts against the stud or rigid abutment, so that by the time the stitch-frame arrives in position for the open clamp to receive the material containing the buttonhole to be stitched the clutch has been opened, thus completely stopping the rotation of the shaft which imparts movement to the stitch-frame, leaving all parts of the machine at rest. The closing of the clamp on the material applied thereon effects the release of the

lever having the stud or abutment, so that the spring referred to connected with the lever having the incline acts to immediately effect the reengagement of the clutch to start the stitching-frame at its highest speed, such speed being continued until the buttonhole-cutting mechanism has been operated to cut the buttonhole and until the stitching mechanism is brought into proper relation to the work held in the cloth-clamp, at which time the stitching mechanism is started automatically into operation, as will be described, and the arm of the rock-shaft again acts upon the lever having the incline to immediately turn it and effect the unclutching of the clutch.

Figure 1 of the drawings represents in side elevation a sufficient portion of a buttonhole-sewing machine of the class referred to, to which my improvements are added. Fig. 2 is an under side view of said machine. Fig. 3 is a partial left-hand side view and broken-out section of the machine shown in Fig. 1. Fig. 4 is an under side view of the cam for actuating the stitch-forming and other mechanisms. Fig. 5 is a detail showing one-half of the clamp and its carrier-plate. Fig. 6 is a detail showing the clamp-frame with the stitch-forming mechanism removed, said view showing the upper side of the main cam and the levers lying above it. Fig. 7 is a detail showing in perspective the arm 53, to be described. Fig. 8 is a front elevation of the lower stitch-forming mechanism and adjacent parts.

The stitch-frame a , the clamp-frame a' , the shaft a^2 , mounted in the stitch-frame and actuating the stitch-forming mechanism, said stitch-forming mechanism containing a needle-bar b' , provided with an eye-pointed needle, the constantly-driven pulley f^{10} , loose on the shaft a^2 , the dog f^{12} , which by its movements is made to secure said pulley to said shaft when the latter is to be rotated to actuate the stitch-forming mechanism, the arm f^{14} , having the stud or projection f^{13} to at times meet the dog f^{12} , said arm forming part of a three-armed rock-shaft, the other two arms being marked F and f^{16X} , the casing f^4 , connected to and moving in this instance with the stitch-frame, the cam-wheel j in said casing, it having a series of worm-teeth at its edge to be engaged by a worm t^6 , fast on a shaft b^{36} , the arm b^{17} , fast on one end of said shaft and having a projection b^{16} to form part of a clutch, the pulley b^{27} , having a hollow sleeve which is fitted over said shaft and having fast upon it a grooved collar b^{18} , the link f^9 , deriving its operation from a suitable eccentric connected with the shaft a^2 of the stitch-forming mechanism, the slide-pin c^{10} , which acts on the arm F of the said three-armed rock-shaft to turn it at the proper times so that the projection f^{13} leaves its dog and permits it to engage the pulley f^{10} with the shaft a^2 to rotate it and start the stitch-forming mechanism, as in Fig. 1, or to effect the engagement of said projection with said

dog and stop the rotation of said shaft, and the arms 29 , pivoted at 30 and having projections 28 to coöperate with the levers or arms, 70 to be described, of the cloth-clamp, the stud l , mounted in a suitable ear attached to and movable with the cam-casing f^4 of the stitch-frame, and the lever l^2 , fixed on said stud and having a roller or other stud l^3 , which enters a cam-groove 7 (see Fig. 4) at the lower side of the cam j and may be all substantially as shown and indicated by like characters in Patent No. 494,280. Herein the cam-groove 150 in the upper side of the operating-cam j is shaped somewhat differently from the shape given to the cam-groove in the upper side of said operating-cam in said patent, and so also the cam-groove B^6 in the under side of said operating-cam j , (see Fig. 4,) it surrounding the cam 7 , is somewhat differently shaped from the cam-groove at the under side of the operating-cam in said patent. The change of shape in the cams 150 and B^6 is such that the operating-cam j may travel for a greater distance during the operation of stitching each buttonhole than the like operating-cam does in the patent referred to, and thereby it becomes possible for said cam B^6 , acting on a roller-stud B^4 of a lever B^2 , to turn the sector 95 A^7 , with which it is operatively joined, for a sufficient distance to rotate the stitch-forming mechanism for a full or more than a full rotation during the formation of each buttonhole. The cam-groove 150 in the upper side 100 of the operating-cam j is entered by a roller or other stud f^7 , (see dotted lines, Figs. 1 and 3,) depending from the clamp-frame, said stud being substantially the same as shown in said patent, and said cam 150 in its rotation acting on said stud imparts to the stitch-frame longitudinal motions to carry the stitch-forming mechanism in the proper lines to stitch a buttonhole held in a clamp carried by the clamp-frame, the latter being stationary; but 110 it will be understood that this invention comprehends either moving the stitch-frame longitudinally or the clamp-frame longitudinally, as in either plan the operation is the same.

The machine described in United States Patent No. 494,280 contains a single starting and a stopping cam, the cam being provided at one end with an incline to start into operation the stitch-forming mechanism at a definite time, the opposite end of said cam being 115 made abrupt to stop the operation of said stitch-forming mechanism instantly. In that patent the starting and stopping point of the cam always occupied exactly the same distance apart, and if the starting-point was adjusted to vary the starting of the stitching the stopping-point was correspondingly adjusted and the stitching was always of the same length. Said starting and stopping cam has been made in multiparts, so that any desired adjustment may be had between the points of starting and stopping. Making said cam adjustable as to its effective length enables the stitching to be started at any desired

point with relation to the buttonhole and the stitching to be stopped at any desired point, and by rotating the stitch-forming mechanism for more than one rotation in the operation of stitching each buttonhole the points of stitching in starting and stopping may be made to cross each other.

Referring to Fig. 6, 157 represents the starting-point of the starting and stopping cam, 10 and 153 the stopping-point of said cam. The starting-point is held adjustably in position by a suitable set-screw 152, while the stopping-point is held in position by a suitable set-screw 154, an intermediate portion 155 of 15 said cam being held in place by a suitable set-screw 156. It will be noticed that the inner ends of the starting and stopping points of the cam are beveled at their junction with the intermediate portion 155 of the cam, so 20 that in no instance are the gaps between the starting and stopping portion and the intermediate part opened sufficiently to let descend into the space between said parts the lower end of the pin or stud c^{10} , which rides 25 on said cam and controls the clutch for starting into motion and actuating the shaft a^2 , that it may assume control of and rotate the shaft b^{36} intermittently at its slower speed during the stitching of a buttonhole.

30 The needle-bar slides up and down in a box 34, having an attached gear 39. The under-thread-carrying needle 51^x is mounted upon a segment 50^x , sliding in a curved raceway 49^x , and operated from the reciprocating hollow rod 59 by means of the lever 54^x and connected parts, as described in the aforesaid Patent No. 498,216. The looper 63^x , which co-operates with the under-thread-carrying needle 51^x and the eye-pointed needle of the 40 needle-bar b' in making the stitch, is given its proper movements by the hollow rod 59, which reciprocates the block carrying the cam-groove 70^x for actuating the roller 69^x and also carrying the projection 71^x for actuating 45 the adjustable projection 72^x , all as fully described in the aforesaid Patent No. 498,216. The hollow rod 59, the lever 60, pivoted at 61 and connected with the link f^9 , the block 48, on which said rod 59 slides, the gear 45, 50 attached to the lower end of said block below its bearing 46, forming part of the case f^4 , and the lever 54^x , moving the segment containing the under-thread carrier, operate and are all as shown and described in the aforesaid Patent No. 498,216.

55 The casing f^4 sustains a vertical rock-shaft A, having a collar A', which rests on a part of the casing to thus maintain the said rock-shaft in its vertical and operative position. 60 The upper end of this rock-shaft has connected to it by a screw A² the hub A³ of a toothed sector A⁴, said sector engaging the gear 39 for imparting rotary movement to the needle-bar. The shaft A at its lower end has fast to it by a 65 screw A⁵ the hub A⁶ of a sector-lever A⁷, the teeth of said sector-lever engaging the gear 45, fast on the box 48, to thus effect the rota-

tions of the said box and the under-thread carrier and looper mounted therein. The short arm A⁸ of the sector-lever A⁷ has adjustably 70 connected to it by an adjusting-screw B a link B', jointed to one end of the lever B², pivoted at B³ on a part of the casing f^4 , said lever having a roller or other stud B⁴ mounted thereon and made adjustable in a slot B⁵ thereof. 75 The roller-stud enters the cam-groove B⁶ (see Fig. 4) at the under side of the cam j, mounted inside the casing, and as said lever B² is moved it moves the sector-lever A⁷, causing it to turn the shaft A, so that both the sectors A⁷ and A⁴ in engagement with the respective gears 45 and 39 rotate the stitch-forming parts simultaneously and in unison, and owing to the fact that the said sector-levers are fast on and move with the shaft A, 80 said shaft constituting their fulcrum or center of motion, it becomes possible to move said sectors for a distance sufficient to effect a full revolution of the gears 45 and 39 during the formation of each buttonhole, one half of the 85 full revolution being imparted when making, say, the large eye of the buttonhole and the other half when starting and completing the small end of the buttonhole. In fact, the extent of motion given to the sectors may be 90 and in practice usually is sufficient to give a little more than one complete rotation to the stitch-forming mechanism during the production of each buttonhole. The buttonhole having been finished and the stitch-forming mechanism having been stopped and the cloth-clamp opened the sectors are reversed in 95 their movements, reversing the movement of the stitch-forming mechanism and bringing the same back into starting position, so that when the stitching of the next buttonhole is to be begun the stitching may be commenced at one side of the slit, near one end, preferably its small end. By reversing the movement of the stitch-forming mechanism after 100 the formation of each buttonhole the tendency to twist the threads used in forming the stitch is obviated.

The rod 59 is hollow, (see Fig. 2,) as provided for in Patent No. 498,216, and the under or second thread is led therethrough from a suitable spool supported upon the table or other fixed part of the machine.

115 The arms C, carrying the upper member C' of the cloth-clamp, are mounted on a suitable pivot C², extended through a block C³, adjustably connected by a screw C⁴ in a slot of said block to a plate C⁵, there being two such plates and levers placed in a suitable recess in the clamp-frame. The under member of the cloth-clamp is and may be all as provided for in either of the two patents referred to. The shorter arms of the levers C have (see Fig. 1) inturned ears D, which are overlapped by the projections 28 of the clamp-closing arms or levers 29, there being a space above each ear. One of the clamp-closing levers 29, (see Fig. 3,) there being two such levers fast on the rod 30, has attached to it by a screw D' the flanged

end D² of an arm D³, provided at its free end with an adjusting-screw D⁴, having at its upper end a loose block D⁵. The flange D² in this present instance of this invention carries 5 an adjusting-screw D⁶ and a stop-screw D⁷, and the spring D⁸ connects a convenient portion of the frame to the arm D³, which spring normally acts to lift the said arm and the arms 10 29 to open the cloth-clamp. The screw D⁶ and its carrying means constitute locking means for an initial starting-lever E', to be described.

The drawings, Figs. 1 and 3, show the clamp in the position it will occupy when closed 15 upon the work, and in such position the end of the screw D⁶ is below and out of contact with the projection 31 at the end of said lever E', pivoted on a stud E², carried by the clamp-frame, the rear end of said lever being slotted, 20 as at E³, to receive a stud E⁴, which is made adjustable in said slot, said stud extending downwardly across the path of movement of a switch (shown as a lever G) to be described. The casing f⁴ has a pivot G', upon which is 25 mounted one end of the switch G, said switch having one of its arms slotted, as at G², to receive the arm f^{16X} of the three-armed rock-shaft, said arm contacting with the end 30 of the slot in said lever while a buttonhole is 30 being stitched and keeping said lever in the position Fig. 6, with the spring G³ strained. In this condition of the switch G a roller or other stud G⁴, carried by one end thereof and standing in the groove of the collar b¹⁸, holds 35 the clutch-pulley b²⁷, with its projection G⁵, back away from and out from engagement with the projection b¹⁶ of the arm b¹⁷, so that said continuously-driven clutch-pulley b²⁷, although rotating, remains inactive, the shaft 40 b³⁶ at such time being rotated at its slowest speed by means which will be hereinafter described. When the stitching of the buttonhole has been completed, it is desirable that the speed of the shaft b³⁶ be increased 45 momentarily, and to do this the following provision has been made, viz: That arm or end of the switch G near the roller-stud G⁴ is beveled or inclined, as at 20, (see dotted lines, Fig. 6,) and the stud E⁴ crosses the line of 50 said bevel or incline. The lever E' is acted upon by a spring H, a part of which is enclosed in a suitable hole 21 of said lever, the opposite end of the spring entering an opening in a portion of the clamp-frame a', where 55 its end is acted upon by an adjusting-screw 22. (See Fig. 3.) This spring H acts normally to keep the stud E⁴ pressed toward the inclined part of the switch G, it being used simply to insure contact.

60 The casing f⁴ has a suitable ear 23, (see Fig. 3,) provided with a stud 24 on which is mounted a clamp-closing lever H', said lever normally resting at its free end on the block d⁵ and having, as shown, a suitable roller or 65 disk H², which is acted upon by the under side of the operating-cam j, said cam having

in it, as shown, a depression j', (see Fig. 4,) in which may enter said roll when it is desired to open the clamp to effect the release of the material and the reapplication of the 70 material to the clamp preparatory to making another buttonhole. When the roller H² enters the said recess, the spring D⁸ acts to lift the arm D³ and with it the arms 29, causing their projections 28, acting in the inturned 75 ears of the arm of the levers C, to turn them sufficiently to remove the upper members C' of the clamps from the work, and at such time the stop-screw D⁷ meets the under side of 80 the clamp-frame, said screw being adjusted as may be desired to insure the proper or necessary opening movement of the clamp.

The drawings, Figs. 1 to 3 and 6, show the parts in the positions they will occupy when the buttonhole is being stitched. 85

It will be remembered that the rock-shaft having the three arms f¹⁴, F, and f^{16X} is moved by the spring f²² to stop the rotation of the shaft a², which actuates the stitch-forming mechanism, when the sliding pin c¹⁰ passes 90 over the stopping end 153 of the starting and stopping cam, the passage of said pin from said cam permitting the arm f^{16X} to be turned in the direction of the arrow near it in Fig. 1, so that the said arm retires from its contact 95 with the end 30 of the slot G², letting the spring G³ turn the switch G so that it contacts at its side near the base of said incline 20 with the stud E⁴, and as the arm f^{16X} is turned to let the switch G move, as described, 100 the cloth-clamp is instantly opened, so that the adjusting-screw D⁶ carried thereby comes up opposite the inner end 31 of the lever E' and immediately locks said lever in a fixed 105 position.

The movement of the switch G due to the spring G³ causes the roller-stud G⁴ of said lever, standing in the grooved collar b¹⁸, surrounding the shaft b³⁶ loosely and fast on the sleeve of the clutch-pulley, to immediately 110 move the clutch-pulley b²⁷ in the direction of the arrow 10 near it in Fig. 6, causing the projections G⁵ and b¹⁶ to engage, thus closing the clutch, and thereafter the pulley b²⁷ controls the movement of the shaft b³⁶ at its 115 higher rate of speed, and immediately the said operating-cam j is started up at high speed and the stitch-frame is moved longitudinally at a faster speed, causing the incline 20 to act against the then stationary stud or 120 fulcrum E¹, and as the stitch-frame arrives in its position to receive new work the incline 20 will have traveled over said stationary stud or fulcrum sufficiently to have moved the pulley b²⁷ in a direction opposite the arrow in 125 Fig. 6 to effect the disengagement of said pulley from the arm b¹⁷, fast on said shaft, leaving the said shaft at rest, for it will be understood that when the stitch-forming mechanism was stopped by the movement of the 130 three-armed rock-shaft movement of the shaft a² was also stopped, and consequently the

mechanism between said shaft and the shaft b^{36} for imparting to the latter its slower movements was thrown out of operation.

The mechanism for cutting the buttonhole-slit is constructed and operated as shown in either of the said two patents, Nos. 494,280 and 498,216. The cam device for actuating the stitch-forming and other mechanisms has at its upper side, near its center, a cam 57^x , which acts on a toe 58^x of a cutter-carrying lever G^x , pivoted at G^x and provided with a cutting-blade G^{2x} of the length of the button-hole to be cut, said pivot G^x being held in suitable ears on the stitch-frame. The buttonhole-cutting blade operating as a single-stroke cutter cooperates with a suitable cutter bed or anvil of the usual form, shown in the two said patents and hence not considered necessary to be here illustrated. The cutter is thus given its downward or cutting movement by the action of the cam projection 58^x , and a spring G^{3x} , as usual, provides for the upward movement of the cutter.

With the cloth-clamp open and the stitching-frame and its stitch-forming mechanism in such position away from said clamp as to enable the work to be reinserted in the clamp the clamp will be closed upon the work, and in so doing the clamp will depress the arms 29 and with them the arm D^8 , removing the screw D^6 from contact with the lever E' , and immediately the spring G^8 will act to move the lever G in the direction of the arrow 10, Fig. 6, said lever carrying with it the stud or fulcrum E^4 , it being no longer restrained by the adjusting-screw D^6 , causing the said lever G to slide the continuously-rotating pulley b^{27} , and put its projection G^5 in contact with the projection b^{16} of the arm b^{17} , fast on the shaft b^{36} , immediately starting the stitch-frame at its high rate of speed, causing the buttonhole-slit to be cut and the stitch-frame and stitching mechanism to be put into position where the first stitch is to be made in 45 the commencing of a buttonhole, the slide-pin c^{10} is elevated by the inclined end of the cam 157, turning the said three-armed rock-shaft and removing the projection f^{13} from the end of the dog f^{12} , letting said dog move 50 under the spring 34 to effect the engagement of the continuously-rotating loose pulley f^{10} with the shaft a^2 for operating the stitch-forming mechanism, so that said shaft immediately starts and sets into operation the 55 stitch-forming mechanism. Movement of the three-armed rock-shaft, as described, causes the arm f^{16x} to move in a direction opposite the arrow near it in Fig. 1, said arm meeting the shoulder 30 of the lever G and pulling said 60 lever in opposition to its spring G^8 causes the roller-stud G^4 at the end of said lever acting in the collar b^{18} to immediately disengage the projection G^5 of the continuously-rotating pulley b^{27} from the projection b^{16} of 65 the arm b^{17} , fast to said shaft b^{36} , leaving said shaft free to be moved at the slower speed during stitching by devices now to be de-

scribed, deriving their movement from the shaft a^2 of the stitch-forming mechanism. The shaft b^{36} has fast upon it a collar J , and at one side of said collar the shaft has fixed to it a gear 40, and about this gear is hung an internally-toothed ring 41, some of the teeth of the ring engaging the teeth uppermost in the gear, one side of the ring resting against the collar J . The outer end of the shaft b^{36} has loosely mounted upon it a pawl-carrier 50, provided with a biting dog or pawl 51, which acts on the smooth periphery of the ring 41 as the pawl-carrier is moved downwardly, said pawl-carrier deriving its movements from a link 52, connected with an arm 53, extended from a hollow hub surrounding the rock-shaft having the three arms, as described, said hub having a second arm, (see Fig. 7,) which is acted upon at suitable times by an eccentric marked f^{39} , (see Fig. 7,) said eccentric being substantially the same as the eccentric marked f^3 in said Patent No. 494,280. In the space between the teeth at the lower edge of the wheel 40 and the teeth of the ring 42 there has been placed a crescent-shaped wedge 54, it having a pin 55, with which is connected a spring 43, the opposite end of said spring being attached to a stud 44 of the pawl-carrier 50, so that said wedge follows the active movement of the pawl-carrier, and the spring acts to draw the wedge out from between the teeth of the gear and the ring while the pawl 51 is returning for a fresh grip on the ring, the wedge insuring the engaging of the teeth of the positively-driven ring with the teeth of the gear, and in this way the gear 40 and the shaft b^{36} are driven intermittently during the stitching of the buttonhole. By the use of this ring and gear the employment of a pawl and ratchet is obviated.

Having described the invention, what is claimed, and desired to be secured by Letters Patent, is—

1. In a machine for stitching buttonholes, the following instrumentalities, viz: a cloth-frame, a clamp mounted thereon, a stitch-frame containing part of the stitch-forming mechanism comprising a needle-bar and needle, a gear surrounding the needle-bar of the stitch-forming mechanism, a block containing the stitch-forming mechanism complementary to said needle-bar and needle, a second gear carried by said block, a vertical rock-shaft, two toothed sectors mounted on said rock-shaft, means to turn said rock-shaft and actuate said toothed sectors each for a distance sufficient to rotate both said gears for a distance in excess of one complete rotation, a part of said complete rotation being effected at each end of the buttonhole, and means on the completion of the buttonhole to reverse the movement of said stitch-forming mechanism and turn it back into its normal or starting position.
2. In a machine for stitching buttonholes, the following instrumentalities, viz: a stitch-

frame having a casing, an operating-cam having a cam-groove, means to rotate said operating-cam, a pivoted lever movable with said casing and the stitch-frame, a stud carried by said lever and entering a groove in said operating-cam, a sector-lever having an arm, means to connect the lever movable with said casing and stitch-frame with said sector-lever, a rock-shaft to which said sector-lever is fixed, a second sector-lever carried by said rock-shaft near its upper end, two gears each engaged by one of said sector-levers, and stitch-forming mechanism rotated in unison by said sector-levers engaging said gears, said sector-levers being actuated for a distance sufficient to impart to said gears and the stitch-forming mechanism a movement in excess of a full rotation, and means to then reverse the movement of said sector-levers and stitch-forming mechanism, putting the stitch-forming mechanism into its normal or starting position.

3. In a buttonhole-stitching machine, a stitch-frame having a casing, stitch-forming mechanism mounted in said stitch-frame, said stitch-forming mechanism comprising an eye-pointed penetrating needle and a complementary under-thread-carrying needle, an operating-cam inclosed in said casing, and means to rotate said operating-cam; combined with a lever pivotally mounted upon and movable with said casing and stitch-frame, an adjustable roller-stud carried by said lever and entering a groove in said operating-cam, a sector-lever, an independent fulcrum therefor, said sector-lever engaging a gear operatively joined to the complementary stitch-forming means, and a jointed connection between the lever movable with the casing and stitch-frame and the end of said sector-lever, to operate, substantially as described.

4. In a buttonhole-stitching machine, stitch-forming mechanism comprehending an eye-pointed penetrating needle and complementary devices carrying an under thread, means to actuate said stitch-forming mechanism to form overedge-strokes, and means to rotate said stitch-forming mechanism for a distance greater than one rotation thereof during the formation of a buttonhole, means to suspend the operation of said stitch-forming mechanism at the completion of a buttonhole, and means to thereafter reverse the rotation of said stitch-forming mechanism and return it to its normal starting position.

5. In a buttonhole-stitching machine, stitching mechanism including an eye-pointed penetrating needle, an under-thread carrier, and a looper; means to actuate said stitch-forming mechanism to form a series of overedge-strokes, and means to cause said stitch-forming mechanism to operate along the sides of the buttonhole, means for imparting to said stitch-forming mechanism a semirotative movement at opposite ends of the buttonhole,

said semirotations being in the same direction, the extent of rotative movement given to the stitch-forming mechanism in making a buttonhole being more than one full rotation whereby the buttonhole is stitched about both ends, means to suspend the operation of the stitch-forming mechanism at the completion of the buttonhole, and means to thereafter turn said stitch-forming mechanism in the reverse direction returning it to its normal starting position.

6. In a buttonhole-stitching machine, a stitch-frame carrying stitch-forming mechanism including an eye-pointed penetrating needle, an under-thread carrier and looper; a clamp-frame; a shaft mounted in said clamp-frame, an operating-cam carried by said clamp-frame and rotated by said shaft intermittently step by step during the operation of stitching a buttonhole, a starting and stopping cam adjustable in position and as to its operative length and carried by said operating-cam, and means controlled by said starting and stopping cam to start into operation and stop the action of said stitch-forming mechanism that the stitching may be commenced at the desired point in a buttonhole and be carried entirely about the buttonhole, the stitch-forming mechanism during such operation being rotated in one direction for more than a full rotation thereof, at which time the stopping mechanism acts to effect the stopping of the stitch-forming mechanism, further rotation of said operating-cam by said shaft, the stitching mechanism being at rest, reversing the said stitch-forming mechanism and returning the stitch-frame into its starting position.

7. In a machine for stitching buttonholes, a stitch-forming mechanism consisting of a reciprocating eye-pointed needle and complementary means coöperating therewith and to form an overedge-stitch, a support for said complementary stitch-forming means, a clamp to hold the work, cloth-cutting means, means to actuate it to cut the work in the clamp, means to actuate said stitch-forming mechanism, means to rotate said support in one direction intermittently for more than one complete rotation while the stitch-forming mechanism is actuated to stitch a buttonhole and bar one end thereof, and means to thereafter rotate said support with its complementary stitch-forming means in an opposite direction while the stitch-forming mechanism is inoperative.

8. In a machine for stitching buttonholes, a clamp-frame, a clamp to hold the work, a stitch-frame, stitch-forming mechanism therein including an eye-pointed penetrating needle and complementary parts to control a second thread, means to actuate said stitch-forming mechanism to make overedge-strokes, means to control the time of starting said actuating means, and the commencement of the stitching, means to change the relative posi-

tions of said stitch-forming means and clamp-frame according to the size of the buttonhole to be stitched, means to impart to said stitch-forming mechanism during the formation of 5 a buttonhole a circular motion in excess of one entire rotation, means to stop said actuating means at the completion of the rotative movement of the stitch-forming mechanism and to then reverse the movement of said 10 stitch-forming mechanism, returning it to its normal starting-point.

9. In an organized buttonhole-stitching machine, a work-clamp, work-cutting mechanism, stitch-forming mechanism including an 15 eye-pointed penetrating needle and complementary under-thread-carrying means, means to actuate said cutting mechanism to cut the work, means to then start the sewing mechanism to overstitch the edges of the button- 20 hole, means to rotate the said stitch-forming mechanism in one direction for more than a full rotation to thereby enable the last stitches made in finishing the buttonhole to overlap 25 stitches made at the commencement of the buttonhole, and means to thereafter reverse the rotation of said stitch-forming means and bring it into its normal starting position.

10. In a buttonhole-stitching machine, the following instrumentalities, viz: a stitch- 30 frame, a clamp to hold the work, actuating-arms having projections to open and close said clamp, a depending arm connected with the actuating-arms, a casing connected with said stitch-frame, a lever pivotally mounted 35 on said casing and provided with a stud, said lever having operative contact with said depending arm, and a rotating cam shaped to actuate the lever carrying said stud and effect the closing of the clamp automatically at 40 the proper time.

11. In a buttonhole-stitching machine, the following instrumentalities, viz: a stitch-frame, a clamp-frame, a work-holding clamp mounted thereon, actuating-arms connected 45 with said cloth-clamp and having projections to be acted upon and close said clamp, a depending arm connected with the actuating-arms, a casing connected with said stitch-frame, a lever pivotally mounted on said casing and having its ends normally in contact 50 with said depending arm, a spring acting on said depending arm to open the clamp, and a cam acting on said lever to depress the depending arm and close the clamp at the desired times.

55 12. In a buttonhole-stitching machine, a cloth-clamp having depending arms, an arm having a device to engage said depending arms and provided with an adjustable stop a change of position which limits the extent of 60 opening of the clamp to adapt the same for receiving work of varying thickness.

65 13. In a buttonhole-stitching machine, a cloth-clamp, means in engagement with said cloth-clamp for moving the same in one or the other direction, a closing-lever, means to operate it, and adjusting means between said

closing-lever and the means for opening and closing said clamp, whereby the degree of pressure of the clamp upon the goods may be 70 determined.

14. In a buttonhole-stitching machine, a clamp, an arm having ears engaging depending arms of said clamp, a depending arm carried by the arm having the ears, an adjustable stud in said depending arm, a spring connecting a suitable point on the frame of the machine and said depending arm to open the clamp, and a closing-lever coöperating with said depending arm to close the clamp at the 80 proper time and means for operating said lever.

15. In a buttonhole-stitching machine, the following instrumentalities, viz: a shaft having a worm, said shaft also having an arm with a projection, an operating-cam having worm-teeth engaged and adapted to be rotated by the worm of said shaft, a stitch-frame carrying said operating-cam and shaft, a continuously-rotating high-speed clutch-pulley mounted loosely on said shaft, stitch-forming mechanism carried by said stitch-frame, an independent rotating shaft, and means operated thereby to actuate said stitch-forming mechanism, means to start and stop the shaft 95 for operating the stitch-forming mechanism at the desired times, a switch controlled by the means for starting and stopping the shaft for operating the stitch-forming mechanism, said switch having an incline and being operatively connected with a hub secured to said continuously-rotating high-speed clutch-pulley, an initial starting-lever having a stud, cloth-clamping mechanism provided with a stud to hold and release said initial starting-lever at the desired times, whereby when the said initial starting-lever is locked by said latter stud with the cloth-clamp in its open condition the movement of the stitch-frame with the switch having the incline causes said switch to operate and remove the clutch-pulley from engagement with the projection carried by the arm of the shaft having the worm to thereby stop the further rotation of said worm-shaft.

16. In a buttonhole-stitching machine, a stitch-frame, a shaft mounted therein, a continuously-rotating clutch-pulley loose on said shaft, a switch made as a lever and mounted on said stitch-frame, one end of said switch being in operative engagement with a part of a sleeve extending from said clutch-pulley, said switch having an incline; combined with means to move said switch in a direction to effect the engagement of a projection carried by said clutch-pulley with a projection carried by an arm extended from said shaft, means under the control of said shaft to move the stitch-frame longitudinally, a clamp-frame, an initial starting-lever pivoted thereon, means to lock said lever as the stitch-frame is started in its longitudinal movement, a projection carried by said lever being acted upon by the incline of the switch to effect the 110 115 120 125 130

disengagement of the clutch from said shaft when the stitch-frame has been moved longitudinally for the proper distance to at such time release the clutch and leave the shaft 5 actuated by it at rest.

17. In a buttonhole-stitching machine, a cloth-frame, a cloth-clamp carried thereby, and operatively connected with a stud to lock an initial starting-lever, said cloth-clamp being pivotally mounted on said clamp-frame, an initial starting-lever pivoted on said clamp-frame and provided with a stud, a stitch-frame having a shaft, a continuously-rotating clutch-pulley mounted loosely on said shaft, a switch, 15 a spring controlling said switch to effect the engagement of said rotating clutch-pulley with said shaft to start it at its highest speed, said shaft actuating the stitch-frame and causing the incline on the switch acting 20 against the stud of the initial starting-lever to disengage the clutch referred to and stop the rotation of said shaft.

18. In a buttonhole-stitching machine, a shaft having an arm provided with a projection, 25 a constantly-rotating pulley loosely mounted on said shaft and provided with a projection, a cloth-clamp, means to retain said cloth-clamp in its open position, an initial starting-lever controlled by said cloth-clamp 30 and operatively held in its abnormal position by said open clamp, a switch under the control of a spring to normally effect the engagement of the projection of said clutch-pulley with the projection of the arm fast on said 35 shaft, the closing of the clamp releasing the initial closing-lever permitting the spring to act upon and turn the switch to engage the clutch-pulley with the shaft.

19. In a buttonhole-stitching machine, the 40 following instrumentalities, viz: a stitch-frame, a shaft mounted therein having a worm, an operating-cam carried by said stitch-frame, said cam having worm-teeth adapted to be engaged and rotated by the worm of said shaft, 45 a continuously-rotating high-speed clutch-pulley mounted loosely on said shaft, stitch-forming mechanism mounted in said stitch-frame and actuated from a primary shaft a^2 , means to start and stop said primary shaft to 50 operate or leave at rest the stitch-forming mechanism at the desired times, a switch having an incline at one end and held in one of its positions by the means for starting or stopping said primary shaft, means to connect 55 said switch with the hub of said continuously-rotating high-speed clutch-pulley, an initial starting-lever having a stud, a cloth-clamp, and means intermediate said cloth-clamp and said initial starting-lever to lock and then release 60 the latter lever at the desired times, whereby when the said initial starting-lever having said stud is locked by or through the cloth-clamp, the movement of the stitch-frame with the switch having the incline causes said 65 incline acting against said initial starting-lever to disengage a projection from said clutch-pulley from a projection of the shaft having

the worm, and a spring to move said switch when the initial starting-lever is released by the closing of the cloth-clamp, said spring at 70 such time immediately effecting the engagement of the clutch and the immediate starting of the shaft having the worm at its high rate of speed.

20. In a buttonhole-stitching machine, a 75 stitch-frame having a casing, a switch pivoted on said casing and having at one end an open slot, the other end of said switch having an incline, a high-speed continuously-rotating clutch-pulley, means to connect said switch 80 with said clutch-pulley to slide it on the shaft about which it is rotated, a three-armed rock-shaft having one of its arms engaging said switch, means to actuate said rock-shaft to turn said switch in one direction, a spring to 85 move said switch in an opposite direction, a clamp-frame, a lever pivoted on said clamp-frame, and having at one end a stud; combined with a clamp mounted on said clamp-frame, and means intermediate said clamp 90 and said lever to hold the latter in fixed position when the clamp is open to receive work, said lever being released when the clamp is closed, thus freeing the switch that it may be immediately actuated by its spring to close 95 the clutch and start the shaft at its high rate of speed.

21. In a machine for stitching buttonholes, the following instrumentalities, viz: a cloth-frame, a cloth-clamp mounted thereon; a 100 stitch-frame containing stitch-forming mechanism, a gear having teeth entirely about its periphery and surrounding the needle-bar of the stitch-forming mechanism, a gear having teeth entirely surrounding its periphery 105 mounted on a block containing the stitch-forming mechanism complementary to said needle-bar and needle; a vertical rock-shaft, two sector-levers having said rock-shaft as their center of motion, and means to turn said 110 rock-shaft and impart to said sector-levers a movement sufficient to impart more than a complete rotation to the said gears and the stitch-forming mechanism, a part of such rotary motion being effected at opposite ends of 115 the buttonhole, said sectors in their reverse movement reversing the said gears and turning the stitching mechanism backwardly into its starting position.

22. In a machine for stitching buttonholes, 120 the following instrumentalities, viz: a frame having a clamp to hold the material to be stitched, a stitch-frame containing stitch-forming mechanism, actuating means therefore, means for imparting more than a complete rotary movement to said stitch-forming mechanism, part of such rotary movement being imparted at one period in the operation of stitching the buttonhole, and the remainder 125 of such rotary movement being imparted at another period in the operation of the stitching of the buttonhole.

23. A sewing-machine, comprising a stitch-forming mechanism, means for imparting to

said mechanism a complete rotation during its sewing operations, and means for reversing said rotation to restore said mechanism to its normal position after the completion of its 5 sewing operations.

24. A sewing-machine of the character stated, comprising a bed-frame, a work-clamping member, an eye-pointed, reciprocating, straight needle located above the clamping member, and complemental stitch-forming mechanism consisting of an eye-pointed, reciprocating curved needle located below the clamping member, means to actuate the needles in forming the stitches, means to rotate the needles, step by step, a full revolution during the stitching operations, and means to reversely rotate the needles back to the starting-point.

25. A sewing-machine of the character indicated, having a work-clamping member, an eye-pointed, reciprocating, straight needle located above the work-clamping member, an eye-pointed, reciprocating curved needle below the work-clamping member, means to actuate the needles for making overseaming stitches, a cam, and means to rotate the cam, said cam having a groove, and connections, substantially as described, with the needle-carrying parts, whereby a partial rotation of the cam causes a full rotation of the needles in one direction and complete rotation of the cam causes reverse rotation of the needles back to the starting-point.

26. A sewing-machine comprising a stitch-forming mechanism and a cutting mechanism, means for actuating said mechanisms

alternately, means for imparting to the stitch-forming mechanism a complete rotation during its sewing operations, and while the cutting mechanism is at rest, and means for restoring both the stitch-forming and cutting mechanisms to position for a repetition of their operations; substantially as described. 40

27. In a sewing-machine of the character indicated, in combination, a bed-frame, a work-clamping member, an eye-pointed, reciprocating, straight needle located above the work-clamping member, and complemental stitch-forming mechanism including an eye-pointed, reciprocating, curved needle located below the work-clamping member, means to actuate the needles in forming the stitches, a cam and means to actuate it, step by step, during the stitching operations, and separate means to actuate it continuously 55 thereafter, said cam having the cam-groove B⁶, and connections, substantially as described, with the needle-carrying parts b', 48, whereby the needles are rotated a full revolution during said step-by-step movement, 60 and reversely rotated to the starting-point during the said continuous movement, substantially as described.

In testimony whereof we have signed our names to this specification in the presence of 65 two subscribing witnesses.
